US0D1015806S

(12) **United States Design Patent** (10) Patent No.: **US D1,015,806 S**
(45) Date of Patent: ** Feb. 27, 2024

(54) **BREWING DEVICE**

- (71) Applicant: **Instant Brands Holdings Inc.**,
Downers Grove, IL (US)
- (72) Inventors: **Jason LePinske**, Schaumburg, IL (US);
Tyler Brunner, Durand, WI (US);
Tania Aldous, Niles, IL (US)
- (73) Assignee: **Instant Brands Holdings Inc.**,
Downers Grove, IL (US)
- (**) Term: **15 Years**
- (21) Appl. No.: **29/909,051**
- (22) Filed: **Jul. 31, 2023**

Related U.S. Application Data

- (63) Continuation of application No. 29/819,133, filed on
Dec. 13, 2021, now Pat. No. Des. 997,620.

(57) **CLAIM**

The ornamental design for a brewing device, as shown and described.

DESCRIPTION

FIG. 1 is a perspective view of a brewing device showing the new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines depict portions of the brewing device that do not form any part of the claimed design.

1 Claim, 7 Drawing Sheets
